CONCENTRATOR TABLE

Filed May 24, 1929

INVENTOR:

Albert H Stebbins
BY Robert A Hayes,
ATTORNEY

UNITED STATES PATENT OFFICE

ALBERT H. STEBBINS, OF LOS ANGELES, CALIFORNIA

CONCENTRATOR TABLE

Application filed May 24, 1929. Serial No. 365,745.

This invention relates to decks for table concentrators, and more particularly to the arrangement of a pair of decks upon a supporting platform to facilitate the removal of the tailings from the decks.

It has been proposed heretofore to mount a pair of concentrator decks side by side upon a supporting carriage or platform, but in these proposed constructions the decks have usually been positioned upon the supporting carriage so that their concentrate walls lie adjacent each other along the central portion of the carriage and the lower sides of the decks from which the tailings are discharged have been disposed away from each other adjacent the opposite edges of the supporting carriage, this construction being employed in order that the tailings from one deck will escape therefrom at one side of the concentrator table and the tailings from the other deck will escape therefrom at the opposite side of the concentrator table.

The present invention relates to a novel deck construction in which a pair of decks are mounted side by side upon a transversely inclined platform so that both decks may partake of the transverse inclination of the platform and the tailings-discharge side of one deck is disposed adjacent the concentrate wall of the other deck.

This novel construction is desirable as it facilitates the supporting of both decks at a transverse inclination, but this arrangement causes the tailings from the upper deck to be discharged therefrom above a longitudinal central portion of the supporting platform. A further feature of the present invention therefore resides in the construction whereby a runway is formed under the lower deck to direct the tailings from the upper deck along the platform under the lower deck and towards the stream of tailings discharged from the lower deck. As a result of this construction the tailings from the two decks are readily directed into a single bin.

Still another feature of the present invention resides in the construction whereby the transverse inclination of the decks may be varied as desired and the inclination of one

deck may be varied with respect to the other deck.

Other features of the invention and novel combination of parts in addition to the above will be hereinafter described in connection with the accompanying drawings which illustrate one good practical form of the invention.

In the drawings—

Fig. 1 is a perspective view of a pair of decks mounted upon the deck supporting structure in accordance with the present invention;

Fig. 2 is a transverse sectional view through the deck mechanism shown in Fig. 1; and

Fig. 3 is a fragmentary section view taken on the line 3—3 of Fig. 2, looking in the directions of the arrows.

In the embodiment of the invention illustrated in the drawing, the deck mechanism to be described is mounted upon a carriage 10 which may constitute an elongated frame, as shown, and this frame 10 is adapted to be mounted upon the base or supporting structure, not shown, of a concentrator table for vibratory movement. Upon the carriage 10 is mounted the transversely inclined platform 11 which may be strengthened transversely by transversely extending beams 12, and this platform is secured along its lower side by hinges 13 to a longitudinally extending side beam 14 of the carriage 10. The upper side of the platform 11 is supported in spaced relation to the carriage 10 by adjustable means such as the adjusting bolts 15 the upper ends of which are bent and are pivotally secured to the ears 16 which are rigidly secured to the upper edge of the platform 11 and the lower ends of the bolts 15 are threaded and are adjustably secured to brackets 17 secured to a side rail 18 of the carriage 10. The construction is such that the transverse inclination of the platform 11 may be varied as desired by adjusting the nuts 19 upon the bolts 15.

Upon the deck carrying platform 11 are mounted, in accordance with the present invention, a pair of decks 20 and 21, the decks being disposed in substantially parallel relation to each other and extend longitudinally

of the platform, and one deck is disposed above the upper half of the platform 11 while the other deck is disposed above the lower half of the platform 11. The decks 20 and 21 are shown as of the dry concentrator type and may be of any well known construction. Each of these decks is shown as having a material supporting surface 22 upon which are mounted the diagonally disposed riffles 23 adapted to direct concentrates up the inclined deck towards the concentrate wall 24, and the materials that accumulate along the concentrate wall may be drawn off beneath the discharge gates 25 to fall into the concentrate receiving trough 26. The materials to be treated are supplied to the deck surfaces from the feed hoppers 27 having the adjustable gates 28 for controlling the flow of the materials onto the deck surface. Air under pressure may be supplied to an air chamber below each deck surface 22 to pass upwardly in a well known manner through apertures formed in the deck surface.

It will be apparent from the foregoing that both decks 20 and 21 are mounted upon the supporting platform so that they slope transversely in the same direction, and the tailings which are crowded upwardly above the riffles 23 will gradually move downwardly towards the lower side of the deck in a well known manner and will escape from the lower side thereof over the tailing discharge board 29. It will be noted that as a result of the arrangement of the decks just described the tailings from the upper deck 20 will be discharged therefrom adjacent the concentrate wall of the lower deck 21. It is necessary to dispose of these tailings and this is accomplished in accordance with the present invention by supporting the lower deck 21 in spaced relation to the platform 11 so that the tailings from the upper deck may flow down the transversely inclined platform 11 under the lower deck 21 towards the flow of tailings discharged from the lower deck 21.

It may be desirable to vary the transverse inclination of the lower deck 21 with respect to the upper deck 20, and this is accomplished in accordance with the present invention, by pivotally securing the upper side of the deck 21 by means of hinges 30 to the upstanding brackets 31, these brackets being arranged in spaced relation to each other lengthwise of the platform 11 to permit the stream of tailings from the upper deck to flow down the platform between these brackets. The lower side of the deck 21 is adjustably supported in spaced relation to the platform 11 by adjustable means such as the bolts 32 the upper ends of which are secured to ears 33 fastened to the lower side of the deck 21 and the lower end portions of these bolts are threaded and are adjustably secured by nuts 34 to the platform 11. The arrangement is such that the transverse inclination of the deck 21 may be

varied as desired with respect to the platform 11 by adjusting the nuts 34.

It will be apparent from the foregoing that the deck supporting mechanism forming the subject matter of the present invention constitutes an extremely simple means for mounting a pair of decks upon a transversely inclined platform so that the inclination of the platform may be imparted to both decks, while at the same time the tailings from the upper deck are readily disposed of by forming a runway beneath the lower deck along which the tailings may flow towards the stream of tailings issuing from the lower deck.

The concentrates traveling along the concentrate trough 26 may be discharged into the concentrate chute 35 and the middlings that escape from the discharge end of a deck may enter the middling receiving chute 36.

What is claimed is:—

1. Deck mechanism for a table concentrator, comprising in combination, a deck supporting carriage, a deck carrying platform mounted on the carriage at a transverse inclination, a pair of decks mounted upon the platform side by side to extend longitudinally thereof and supported by the carriage at a transverse inclination so that each deck will discharge its tailings along its lower side, and means for supporting the deck near the lower side of the platform in spaced relation to the platform so that the stream of tailings from the upper deck will flow down the platform under the lower deck and combine with the stream of tailings from the lower deck.

2. Deck mechanism for a table concentrator, comprising in combination, a deck carrying platform that is supported at a transverse inclination, a pair of decks mounted upon the platform side by side to extend longitudinally thereof and at a transverse inclination to cause the tailings to discharge along the lower sides of the decks, and means for supporting the deck near the lower side of the platform in spaced relation to the platform so that the stream of tailings from the upper deck will flow down the platform under the lower deck toward the stream of tailings from the lower deck.

3. Deck mechanism for a table concentrator, comprising in combination, a deck carrying platform that is supported at a transverse inclination, a pair of decks mounted upon the platform side by side to extend longitudinally thereof and at a transverse inclination to cause the tailings to discharge along the lower sides of the decks, and means forming a runway beneath the deck at the lower side of the platform and adapted to direct the tailings from the upper deck beneath the lower deck toward the stream of tailings from the lower deck.

4. Deck mechanism for a table concentrator

5 tor, comprising in combination, a deck carrying platform that is supported at a transverse inclination, a pair of decks mounted upon the platform side by side to extend longitudinally thereof and at a transverse inclination to cause the tailings to discharge along the lower sides of the decks, means forming a runway beneath the deck at the lower side of the platform and adapted to 10 direct the tailings from the upper deck beneath the lower deck toward the stream of tailings from the lower deck, and means for adjusting the transverse inclination of one of the decks independently of the other.

15 5. Deck mechanism for a table concentrator, comprising in combination, a deck supporting carriage, a deck carrying platform mounted on the carriage for adjustment to different transverse inclinations, a 20 pair of decks mounted upon the platform side by side to extend longitudinally thereof and supported at a transverse inclination so that each deck will discharge its tailings along its lower side, and means forming a 25 runway along the platform beneath the lower deck for directing the tailings from the upper deck beneath the lower deck toward the stream of tailings discharged from the lower deck.

30 6. Deck mechanism for a table concentrator, comprising in combination, a deck supporting carriage, a deck carrying platform mounted on the carriage for adjustment to different transverse inclinations, a 35 pair of decks mounted upon the platform side by side to extend longitudinally thereof and supported at a transverse inclination so that each deck will discharge its tailings along its lower side, means forming a runway along 40 the platform beneath the lower deck for directing the tailings from the upper deck beneath the lower deck toward the stream of tailings discharged from the lower deck, and means for adjusting the transverse inclination of one of the decks independently of the 45 other.

7. Deck mechanism for a table concentrator, comprising in combination, a deck carrying platform that is supported at a transverse inclination, a pair of decks mounted upon the platform to extend longitudinally thereof and arranged so that one deck is positioned above the upper half of the inclined platform and the other deck is positioned 50 above the lower half of the inclined platform, and each deck being supported at a transverse inclination and constructed with a concentrate wall along the upper side of the deck and a tailing discharge along the lower 55 side of the deck, the tailing discharge of the upper deck being disposed in close proximity to the concentrate wall of the lower deck.

In testimony whereof, I have signed my name to this specification.

65 ALBERT H. STEBBINS.
